CLAIM

The ornamental design for a foldable electronic device with transitional graphical user interface, as shown and described.

DESCRIPTION

FIG. 1 is a front view of a foldable electronic device with transitional graphical user interface showing our new design in which the foldable electronic device is in an unfolded state and showing the first image in a sequence of a transitional graphical user interface;

FIG. 2 is a rear view thereof;

FIG. 3 is a front view thereof showing our new design in which the foldable electronic device is in a folded state and showing the second image in a sequence of a transitional graphical user interface; and,

FIG. 4 is a rear view thereof.

The dashed broken lines showing a foldable electronic device illustrate environmental subject matter and form no part of the claimed design. The remaining broken lines illustrate portions of the article that form no part of the claimed design.

The appearance of the transitional image sequentially transitions between the images shown in FIGS. 1 and 3. The process or period in which one image transitions to another image forms no part of the claimed design.

1 Claim, 4 Drawing Sheets
